CARD CLOTHING STRIPPER

George A. Pettit and Ralph A. Rusca, New Orleans, La., assignors to the United States of America as represented by the Secretary of Agriculture

Application November 21, 1952, Serial No. 321,960

3 Claims. (Cl. 19—108)

(Granted under Title 35, U. S. Code (1952), sec. 266)

A non-exclusive, irrevocable, royalty-free license in the invention herein described, for all governmental purposes, throughout the world, with the power to grant sublicenses for such purposes, is hereby granted to the Government of the United States of America.

This invention relates to the removal of undesired impactions of fibers from the needles of card clothing. More particularly this invention provides a mechanical device adapted for continuously stripping the card clothing of carding machines during the carding operations.

During a carding operation some fibers become impacted upon the needles of the card clothing in a manner in which they are not removed by the fiber removing units of the machine. The amount of impacted fiber gradually builds up to a point at which it interferes with the carding operation.

Various mechanical and pneumatic devices have been developed for stripping card clothing (i. e., removing the impacted fibers) during the carding operation. Pneumatic stripping devices cannot feasibly be controlled as to the amount of impacted fibers they remove and for this reason are usually operated to remove substantially all of the impacted fibers. As is known to those skilled in the art, completely stripped areas of card clothing needles do not card properly until they have again accumulated a certain amount of impacted fibers. The heretofore known continuously operating mechanical stripping devices subject all of the card clothing needles to frequent contact with the stripping needles resulting in considerable wearing of both the clothing and the stripping needles.

An object of the present invention is to provide a means of continuously subjecting operating card clothing to a controlled stripping which removes only the amount of impacted fibers above that amount which is necessary for most efficient carding. A further object is to provide a mechanical stripping apparatus adapted for attachment to standard carding machines which stripping apparatus avoids damages to fibers being carded or to card clothing needles, does not cause nepping of the fibers, and is subject to wear only on inexpensive parts which can quickly and easily be replaced. Further objects and advantages will appear from the following description.

In general the card clothing stripping apparatus provided by this invention comprises: a rotary mechanical stripping element having a stripping area which is small in width in comparison to the width of the area of card clothing to be stripped and provided with stripping needles and means for thrusting said needles radially out from the stripping area of said element, into engagement with the card clothing needles, and withdrawing said needles into said element, to release the impacted fibers impaled upon them as the stripping element rotates; a housing for said element; a support for said element and housing; a means for rotating said element; and a means for moving said element and housing across the area of card clothing to be stripped.

2

In a preferred embodiment of the apparatus, the rotary stripping element comprises a shaft terminating in a disc shaped composite rotor. Said rotor is provided with a circumferential surface pierced with holes, movable needle carriers mounted within said circumferential surface, and cotton working needles mounted in said carriers and lying within said holes. A means for moving the needle carriers as the rotor revolves is arranged to move the needle carriers into positions in which the needles are thrust out through the holes and into engagement with the card clothing needles, when the holes are adjacent to the card clothing, and into positions in which the needles are withdrawn into the holes, as the holes move away from the area of engagement. The housing for the rotary stripping element is arranged to provide a bearing for the rotor shaft and to provide a passageway extending from the area of engagement, of the rotor needles with the card clothing needles, around the circumferential surface of the rotor and back to the area to engagement.

Although in the following description and illustrations the present card clothing stripping apparatus is described with particular reference to its use in cleaning the card clothing on the main cylinder of a standard carding machine, the stripping apparatus can suitably be used to clean the card clothing on revolving flats, doffing rolls and the like processing units. Where a more frequent removal of impacted fibers is desirable, the stripping area of the rotary stripping element can suitably extend across large segments or across the entire area of the card clothing to be stripped. In the latter case the traversing means is, of course, unnecessary.

Figure 1 is an end elevation illustrating the principal parts of one embodiment of the stripper mounted to operate through an opening in the back plate on the main cylinder of a standard carding machine between the lickerin and the forward end of the revolving flats, as the parts would appear when viewed from the left side of the card.

Figure 2 is a pictorial view illustrating the principal parts of the rotary stripping element and its housing as viewed from the right of the center of the main cylinder.

Figure 3 illustrates the disc shaped composite rotor.

Figure 4 illustrates the disassembled principal components of the rotary stripping element and its housing.

Figure 5 is a side elevation with parts removed as viewed from the back of the card.

Figure 6 illustrates a suitable belt and pulley arrangement for rotating the rotary stripping element.

Figure 7 illustrates a suitable arrangement for closing the portion of the opening in the main cylinder back plate not occupied by the rotary stripping element and its housing.

Referring to the preferred embodiment of the stripping apparatus as illustrated by the drawings, the rotary stripping element comprises shaft 1 and disc shaped composite rotor 2. Shaft 1 is supported by bearings 3 and is turned by means of pulley sheave 4. Rotor 2 is centered on the end of shaft 1 and is preferably a continuation thereof.

The circumferential surface of rotor 2 is pierced by holes 5. Movable needle carriers 6 are slideably mounted within the circumferential surface of rotor 2 in slots 7. Cotton working needles 8 are attached to needle carriers 6 and are slideably deposited within holes 5.

The means for moving needle carriers 6 comprises pins 9 attached to the needle carriers and slideably deposited within circular slot 10 in end plate 11 of housing 12. Circular slot 10 is displaced with respect to the axis of shaft 1 toward one side of rotor 2 and thus, as rotor 2 revolves, needle carriers 6 are moved toward that side by the action of pins 9 sliding in circular slot 10. The respective distances are arranged so that as holes 5 reach one side of

the circle through which they travel, needles 8 are thrust out and extend radially from the surface of rotor 2, and as holes 5 reach the opposite side of said circle, pins 8 are at least substantially withdrawn within the circumferential surface of rotor 2.

The housing for the rotary stripping element, housing 12, contains a sleeve portion adapted to receive bearings 3. End plate portion 11 of housing 12 is removably attached by bolts 14. Housing 12 is arranged to provide a passageway 15 extending from the area of engagement between rotor needles 8 and card clothing needles 16, around the circumferential surface of rotor 2 and back to the area of engagement.

Housing 12 and the rotary stripping element it contains are supported by a carrier 13 having grooved wheels 17 at bottom and guiding lugs 19 at top. Support bars 18 which support and guide the carrying unit are attached to brackets 21 which are removably attached to main cylinder back plate 22. Back plate 22 is cut away across the width of the main cylinder to provide opening 23 through which the stripper operates; see Figure 1.

Housing 12 and the rotary element it contains are moved across the area of the card clothing to be cleaned by the action of traversing screw 24 in conjunction with a contacting pawl in sleeve 25 which is attached to carrier 13. The traversing screw is rotated by a conventional drive mechanism not shown. The traversing screw drive pulley or sprocket can be driven from either the extending portion of the lickerin axle, the cylinder axle, or other suitable means.

Pulley sheaves 26 and 27 are rotatably mounted on carrier 13. These sheaves in conjunction with sheaves 28, 29, and 30, rotatably mounted on the card frame, and pulley belt 31 provide a means of rotating sheave 4, which is attached to shaft 1, by means of power supplied to sheave 29, preferably from the cylinder axle.

The portion of the opening 23 in back plate 22 not occupied by the rotary stripping element and its housing is closed by means of closure ribbons 34. The end of one closure ribbon is attached to unit housing 12 and the end of the opposite closure ribbon is attached to end plate portion 11 of housing 12. Each ribbon has a length equal to the width of the main cylinder and they slide freely in guides 32 and 33—thus keeping the unused portion of opening 23 in back plate 22 covered.

The portion of the closure ribbons 34 not covering the opening 23 in back plate 22 slide freely around circular portions and into the straight portion of ribbon holder

the pressure on the pawl and permitting the latter to be free of screw 24.

A means of manually locking rotor 2 in a position in which rotor needles 8 are entirely clear of the card clothing needles is provided by latch 40. In engaged position, the pin of latch 40 enters hole 41 in pulley sheave 4, and thus restrains rotor 2 in neutral position.

For use in cleaning the card clothing on the main cylinder of a card the cleaning area of the rotary stripping element is preferably such that a comparatively narrow portion (about $\frac{1}{2}$ " in width) of the surface of the cylinder clothing will be contacted by the needles of the rotary element. As the element slowly traverses from side to side a continuous spiraling strip of impacted fibers is removed. The card clothing is subjected to only the minimum wear and disturbance necessary to keep the clothing in an ideal operating condition. The needles of the rotary cleaning element are preferably adjusted so that when fully extended they reach into the surface of the card clothing the distance necessary to leave the optimum amount of impacted fibers. The needles are preferably slightly offset or bent near the points to form a modified hook. They are preferably rotated at a surface speed slightly in excess of the surface speed of the card clothing. When they are so shaped and rotated the needles hook and lift the excess fibers which are imbedded in the card clothing. The fibers impaled on the needles are released as the rotor revolves and the needles are retracted at least substantially completely into the holes in the rotary cleaning element. Due to air currents and the pushing and dragging action of other fibers in the path of the needles, the released fibers are moved along the passageway around the rotary cleaning element and are deposited on the points of the card clothing needles.

In the art of textile processing it is well known that carding machines must be stripped at intervals of three to six hours in order to remove the impacted fibers from the clothing. Continued operation of a carding machine without stripping will result in the production of increasingly inferior card sliver, and, if operation is continued without stopping and stripping, a product that is unusable will result.

A comprehensive picture of the performance of this invention on a standard carding machine is reflected from the following data.

A carding machine was ground and thoroughly conditioned before starting the test.

	Amount Carded lb.	Carding Time	Nep Count	Sliver Uni- formity	Remarks
Without Stripping Attachment.	26.5	2 hrs. 15 mins.	31.66	-----	
With Stripping At- tachment.	298.36	27 hrs. 45 mins.	34.37	-----	
Total time 30 hrs. or equivalent to 8 or 10 normal stripping periods.					The slight increase in nep count is due to the thoroughly clean condition of the clothing when first 26.5# were run. Nep count would increase as clothing would gradually become loaded.

35 (Figure 7), as the unit travels alternately across the width of the card. The ribbon holder 35 is attached to shield 36. Shield 36 is removably attached to brackets 21 and extends across the area traversed by the rotary element and its housing.

A means for manually disengaging the rotary element and its housing from the traversing screw 24 is provided by thumb grip bolt 37 (see Figure 5). This bolt operates through the back of carrier 13 to release spring-loaded pin 38 in L-shaped slot 39. The screw-engaging pawl (not shown) is kept in contact with screw 24 by means of pin 38. By pulling out bolt 37, pin 38 may be slipped into the upper arm of slot 39, thereby releasing

At the end of test, the card was producing sliver of normal and uniform consistency indicating that the card clothing was in condition for continued operation without any attention.

The absence of leaf and stem particles imbedded in the clothing due to the action of the stripper provided by this invention is very noticeable.

We claim:

1. A card stripping apparatus comprising a rotary mechanical stripping element, having a stripping area which is small in width in comparison to the width of the area of card clothing to be stripped, and provided with hooked stripping needles and means for thrusting

said needles radially out from the stripping area of said element into engagement with the card clothing needles and withdrawing said needles into said element, to release the impacted fibers impaled upon them as the stripping element rotates; a housing for said element defining a continuous passageway leading from the area of engagement between the stripping needles and the card clothing needles, around the stripping element, and back to the area of engagement; a support for said element and housing; a means for rotating said element at a rate at which the speed of the stripping needles exceeds that of the card clothing needles; and a means for moving said element and housing across the area of card clothing to be stripped.

2. In combination with a carding machine having a main cylinder and a main cylinder back plate; a rotary mechanical stripping apparatus for stripping a continuous spiralling ribbon of impacted fibers from the main cylinder card clothing during the carding operation, comprising: a rotary stripping element and a housing therefor; means for supporting said element and housing adjacent to a traverse slot in the main cylinder back plate; means for moving said element and housing back and forth across said slot; means for continually closing the portions of said slot which are not occupied by said stripping element and housing; and means for rotating said rotary element at a rate at which its surface speed slightly exceeds the surface speed of the main cylinder of the card; said rotary stripping element containing a disc shaped composite rotor, having a cylindrical circumferential surface pierced with holes, arranged to rotate in a direction opposite to the direction of rotation of the main cylinder with its axis parallel to the axis of the main cylinder; said rotor containing hooked textile fiber working needles mounted in movable needle carriers and slideably deposited within

10

20

25

35

holes in the circumferential surface of the rotor; said rotary element housing containing means arranged to coat with the rotation of the rotor and move said needle carriers into positions in which the needles are thrust out into engagement with the card clothing when the holes containing them are adjacent to the card clothing, and into positions in which the needles are substantially completely withdrawn into the holes containing them when the holes are furthest removed from the card clothing, and providing a continuous passageway extending from the area of said engagement around the circumferential surface of the rotor and back to said area.

3. The apparatus of claim 2 in which the needle carriers are transversely slideable within the circumferential surface of the rotor and are provided with pins slideably confined within a circular groove in the rotor housing, said groove lying in a plane parallel to the plane through which the pins move as the rotor rotates and having a center displaced from the center of rotation of the rotor in the direction of the card clothing, so that the needle carriers are moved into the positions in which they thrust out and withdraw the needles by the action of the pins in following the curvature of the groove as the rotor rotates.
